CHAIR

Merritt K. Orton, Grand Rapids, Mich., assignor
to American Seating Company, Grand Rapids,
Mich., a corporation of New Jersey

Application December 16, 1940, Serial No. 370,365

10 Claims. (Cl. 155—115)

The present invention relates to chairs and more particularly to those of the so-called opera type.

The primary objects of the instant invention are to provide a chair of the general character above indicated having a seat which is rearwardly movable on a substantially horizontal plane for a limited distance; to provide such a chair whose seat is upwardly tiltable as well as rearwardly horizontally movable; to provide such a chair whose back is so connected with the seat that a rearward movement of the seat effects a slight forward movement of the upper end of the back and a slight rearward movement of the bottom end thereof; to provide such a chair which when installed as one in a plurality of rows of like chairs and which when occupied provides for ready and convenient egress from and ingress to unoccupied seats in the same row without seriously disturbing the occupant of such an occupied chair or the occupant of a chair immediately rearwardly of such occupied chair; and, to provide such a chair which is comfortable and convenient in use, relatively simple in mechanical construction and reasonably economical in manufacture.

An illustrative embodiment of the invention is shown in the accompanying drawings, wherein:

Figure 1 is a side elevational view of the chair with its seat and back in their respective positions of normal occupancy of the chair;

Figure 2 is a fragmentary front elevational view thereof;

Figure 3 is a side elevational view of the chair similar to that of Figure 1 but showing its seat and back when moved by the occupant thereof to their respective positions in instances wherein a person seeks ingress to or egress from another chair in the same row of chairs and past such occupied chair;

Figure 4 is an enlarged, fragmentary side elevational view of the chair, partly in section, and showing its seat and back in their respective positions of normal occupancy of the chair;

Figure 5 is a sectional view thereof on line 5—5 of Figure 4;

Figure 6 is an enlarged, fragmentary side elevational view of the chair, partly in section, and similar to that of Figure 4 but showing its seat and back when moved by the occupant thereof to their respective positions in instances wherein a person seeks ingress to or egress from another chair in the same row of chairs and past such occupied chair;

Figure 7 is a sectional view thereof on line 7—7 of Figure 6;

Figure 8 is a sectional view on line 8—8 of Figure 6;

Figure 9 is a sectional view on line 9—9 of Figure 6;

Figure 10 is a sectional view on line 10—10 of Figure 4; and

Figure 11 is a sectional view on line 11—11 of Figure 4.

Referring then to the drawings wherein like parts of the structure shown are designated by the same numerals in the several views, the chair there illustrated comprises a pair of spaced vertically disposed standards 10, each provided with an arm rest 11 secured to its upper end in any suitable fashion and in any convenient manner.

Each standard 10 is provided adjacent its lower forward end with a sleeve 12 projecting laterally from its inner surface and an upwardly extending arm 13 is pivotally secured at its lower end by means of a pivot pin 14 embraced within each sleeve 12.

The upper end of each arm 13 is pivotally secured to the forward end of a generally triangularly formed bracket 15 between which pair of brackets the upholstered chair back 16 is secured and a strut 17, here shown as tubular in form, is interposed between the arms 13 to form an equalizer and which strut likewise provides for structural rigidity.

A pair of generally horizontally disposed links 18, each pivotally connected adjacent its rear end to a back supporting bracket 15 rearwardly of the pivotal connection of an upwardly extending arm 13 with its bracket 15, are each pivotally connected adjacent its forward end to a link 19 whose other end is pivotally connected to its adjacent arm 13 below the pivotal connection of said arm with the back supporting bracket 15.

A pair of upwardly extending links 20, each pivotally connected at its lower end to the inner surface of a standard 10, are each pivotally connected at its upper end adjacent the upper end of a back supporting bracket 15. An equalizing strut 21 interposed between the pair of links 18 intermediate the ends of each link and here shown as tubular in form supports an upholstered seat 22 pivotally mounted thereon for upwardly tilting movement between each vertically disposed standard 10. The seat 22 is provided with a bracket 100 adapted to engage the link 18 to check the forward pivotal movement of the seat 22 on the equalizing strut or rod 21.

A stop 23 is mounted on the inner surface of each standard 10 whose rearward end 24 engages a link 20 when the seat 22 is in its normal forward position of occupancy as shown in Figure 4 whereas the forward end 25 of each stop engages an arm 13 in instances wherein the seat 22 is moved rearwardly by the occupant thereof as shown in Figure 6.

Since each link 18 is disposed substantially horizontally in its pivotally connected relation to the seat 22 and since each link 20 is slightly swingable forwardly-rearwardly about its lower pivotal connection, all as best shown in Figures 4 and 6, the seat 22 and back 16 are each forwardly-rearwardly movable to provide ready and convenient egress from and ingress to unoccupied seats in the same row without seriously disturbing the occupant of such a chair or the occupant of a chair immediately rearwardly of such occupied chair.

It will thus be seen that the chair herein shown and described is comfortable in use, is relatively simple in mechanical construction and is reasonably economical in manufacture, and while but one specific embodiment of the invention has been herein shown and described, it will be understood that certain details of the construction shown may be altered or omitted without departing from the spirit of the invention as the same is defined by the following claims.

I claim:

1. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; and a seat supported on the strut.

2. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; and a seat supported on the strut.

3. A chair comprising a pair of spaced vertically disposed standards; a chair back interposed between the standards whose opposite sides

are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; a seat supported on the strut; and a stop interposed between each upwardly extending arm and each upwardly extending link adapted to engage an arm or a link for limiting the forward-rearward movement of the seat and back.

4. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; a seat tiltably supported on the strut; and a stop interposed between each upwardly extending arm and each upwardly extending link adapted to engage an arm or a link for limiting the forward-rearward movement of the seat and back.

5. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; an equalizing strut interposed between the upwardly extending arms; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; and a seat supported on the strut.

6. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair

back; an equalizing strut interposed between the upwardly extending arms; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; and a seat tiltably supported on the strut.

7. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; an equalizing strut interposed between the upwardly extending arms; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; a seat supported on the strut; and a stop interposed between each upwardly extending arm and each upwardly extending link adapted to engage an arm or a link for limiting the forward-rearward movement of the seat and back.

8. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; an equalizing strut interposed between the upwardly extending arms; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back and each having its other link pivotally connected to an upwardly extending arm; a strut interposed between like links of each toggle; and a seat supported on the strut.

connected at its upper end to a side of the chair back; a pair of toggles, each having one of its links pivotally connected to a side of the chair back below the pivotal connection of an upwardly extending arm and each having its other link pivotally connected to an upwardly extending arm; a strut interposed between like links of the toggle; a seat tiltably supported on the strut; and a stop interposed between each upwardly extending arm and each upwardly extending link adapted to engage an arm or a link for limiting the forward-rearward movement of the seat and back.

5 9. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back and each having its other link pivotally connected to an upwardly extending arm; a strut interposed between like links of the toggle; and a seat supported on the strut.

10 15 10. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back and each having its other link pivotally connected to an upwardly extending arm; a strut interposed between like links of each toggle; and a seat supported on the strut.

20 25 30 35 40 45 50 10. A chair comprising a pair of spaced vertically disposed standards; a chair back interposed between the standards whose opposite sides are each provided with a forwardly extending portion; a pair of upwardly extending arms, each pivotally connected at its lower end to a standard and each pivotally connected at its upper end to a forwardly extending portion of the chair back; a pair of upwardly extending links disposed rearwardly of the upwardly extending arms, each pivotally connected at its lower end to a standard and each pivotally connected at its upper end to a side of the chair back; a pair of toggles, each having one of its links pivotally connected to a side of the chair back and each having its other link pivotally connected to an upwardly extending arm; a strut interposed between like links of each toggle; and a seat supported on the strut.

MERRITT K. ORTON.
